(57) CLAIM

The ornamental design for the hair dryer, as shown and described.

DESCRIPTION

FIG. 1 is a left side view of the hair dryer showing my new design;

FIG. 2 is a bottom plan view thereof;

FIG. 3 is a right side view thereof;

FIG. 4 is a top plan view thereof;

FIG. 5 is a front elevational view thereof; and,

FIG. 6 is a rear elevational view thereof.

The broken line showing of the cord in all views is for illustrative purposes only and forms no part of the claimed design.

Applicant disclaims the cord affixed to the handle of the hair dryer as this cord does not form a part of the design.
